RAILWAY SWITCH OPERATING APPARATUS

Robert M. Gilson, Pittsburgh, Pa., assignor to
The Union Switch & Signal Company, Swiss-
vale, Pa., a corporation of Pennsylvania

Application October 11, 1932, Serial No. 637,243

15 Claims. (Cl. 246—242)

My invention relates to apparatus for the operation of railway switches, and particularly to apparatus of the type involving an electric motor for moving the switch to its normal and reverse positions. One feature of my invention is the provision of novel and improved means for protecting the motor against damage in the event that the switch becomes stalled.

I will describe two forms of apparatus embodying my invention, and will then point out the novel features thereof in claims.

The present application is a continuation in part of my copending application, filed Oct. 9, 1929, Serial No. 398,308, for Railway switch operating apparatus, in so far as the subject matter common to the two cases is concerned.

Fig. 1 of the accompanying drawing is a diagrammatic view showing one form of apparatus embodying my invention. Fig. 2 is a modification 20 of the apparatus illustrated in Fig. 1, also embodying my invention.

Referring to Fig. 1 of the drawing, the reference character S designates a railway switch which is operated by an electric motor M, through 25 the medium of suitable operating mechanism which is not shown in the drawing, but which is indicated by the dotted line between the motor and the switch. The motor comprises the usual armature 1 and field winding 2. The switch operating mechanism includes a contact 7—8 which is closed at all times except when the switch is in its reverse position, and another contact 7—9 which is closed at all times except when the switch is in its normal position.

The motor M is controlled primarily by a polarized relay C. Overload protection is provided by a thermal relay T comprising a heating element 10 and a normally closed contact 11. Associated with the thermal relay 10 is an overload 40 relay A which may be of the ordinary neutral type.

The polarized relay C is controlled by a pole-changer P which will usually be operated by a manual lever in an interlocking machine. Relay C is energized by current of normal or reverse polarity according as the pole-changer P is in its normal or reverse position. As shown in the drawing, this pole-changer is in its normal position, so that relay C is supplied with current of 50 normal polarity by virtue of a circuit which passes from terminal B of a suitable source of current, through the pole-changer P, contact 3 of relay C and contact 13 of relay A in multiple, winding of relay C, and the pole-changer P to terminal O of the same source of current. When the pole-

changer P is reversed, the circuit will be the same as before, except that current of reverse polarity will be supplied to relay C.

Relay A is provided with a pick-up circuit which passes from terminal B, through the back point of contact 4 of relay C, winding of relay A and contact 11 of thermal relay T to terminal O. Relay A is also provided with a stick circuit which passes from terminal B through front contact 12 of relay A, winding of relay A, and thermal relay contact 11 to terminal O. 10

The operation of the apparatus is as follows: As shown in the drawing, all parts are in their normal conditions, that is, relay A is energized by virtue of its stick circuit, relay C is energized 15 in the normal direction, and the circuit for motor M is open at switch operated contact 7—9.

I will now assume that the operator desires to reverse the switch S. To do this, he reverses pole-changer P, thereby supplying current of reverse polarity to relay C, so that the polar contacts 5 and 6 of this relay swing to the right. Motor M will then be energized in such direction as to move the switch S to its reverse position, the motor circuit being from terminal B, through the front point of contact 4 of relay C, polar contact 5, motor armature 1, polar contact 6, switch operated contact 7—8, motor field 2, heating element 10 of relay T and front contact 14 of relay A to terminal O. When 30 the switch S reaches its reverse position, this motor circuit will be opened at contact 7—8, so that the motor will stop.

To restore the switch to its normal position, the operator will restore pole-changer P to its normal position, thereby supplying current of normal polarity to relay C, so that the polar contacts of this relay will swing to the left. The motor M will then be energized in such direction as to return the switch S to its normal position, the circuit being from terminal B, through the front point of contact 4 of relay C, polar contact 6, motor armature 1, polar contact 5, switch contact 7—9, motor field 2, thermal relay element 10, and contact 14 of relay A to terminal O. 40 When the switch reaches its normal position, this circuit will be opened at contact 7—9 and all parts of the apparatus will be restored to their normal conditions.

I will now assume that while the switch is being 50 moved from its normal to its reverse position, the switch becomes blocked, so that an excessive current will be drawn by the motor M. This current flowing through the heating element 10 of the thermal relay T will cause contact 11 of this re- 55

lay to open, thereby opening the stick circuit for relay A, so that the latter relay will become de-energized. The motor circuit will then be opened at contact 14 of relay A. The operator may im- 5 mediately restore the lever to its normal or its normal indication position, after which he need take no further action until the indication is received. The movement of said lever will of course open relay C. After a short interval of 10 time sufficient for the heating element of relay T to cool, contact 11 of this relay will again close, and the pick-up circuit for relay A will then be closed at both contacts 4 and 11 so that relay A will become energized. Relay C will then be- 15 come energized in such direction as to restore the switch to its normal position. The operator may thereupon make another attempt to move the switch S to its reverse position, and this may be repeated indefinitely if necessary.

20 The reason for closing the circuit for relay C through contact 3 of this relay is to prevent the neutral armature of this relay from dropping when the overload relay A becomes opened due to an overload on motor M; if contact 3 were not provided, relay C would become deenergized as soon as relay A opens due to the overload, and this would allow the overload relay A to pick up as soon as contact 11 of thermal relay T closes, thus permitting long continued successive appli- 25 cations of heavy current to the switch motor under blocked conditions, which continued applications would probably result in damage to the motor.

30 Referring now to Fig. 2, in which I have provided a separate thermal relay for each direction of motor rotation, the apparatus of this figure permits the operator to restore an ob- 35 structed switch to its initial position immediately, without the necessity for waiting until a thermal relay cools sufficiently to reclose its contact, following an overload.

35 With the apparatus in the normal condition as shown, if the operator desires to reverse the switch, he will reverse pole-changer P, reversing relay D, so that current will be supplied to motor M over a circuit starting at one terminal B, front contact 15 of relay D, wire 16, front contact 17 of relay E, wires 18 and 19, polar contact 20 of relay D, wire 21, armature 1 of motor M, wire 22, polar contact 23 of relay D, wire 24, heating winding 10 of relay T¹, wire 25, controller contact 7-8, wire 26, and field winding 2 to terminal O. Motor M will now move the switch to the reverse position.

40 55 Should the operator wish to restore the switch to the normal position, he will restore pole-changer P and therefore relay D to the condition shown, whereupon motor M will be supplied with current of the proper polarity for restoring the switch to the position illustrated. The motor operating circuit will be similar to that described above, but will include heating winding 10 of thermal relay T², instead of the corresponding winding of thermal relay T¹.

60 65 It will be noted that the holding circuit for overload relay E, which with the apparatus in the condition shown, may be traced from one terminal B, front contact 27 of relay E, wire 28, polar contact 29, wire 30, thermal contact 31-32 70 of relay T², wires 33, 34 and 35, and winding of relay E to terminal O, includes either the thermal contact of relay T² or T¹, according to the position of polar contact 29 of relay D. That is, simultaneously with the transfer of the motor circuit to one or the other thermal relay by a

reversal of relay D, the holding circuit for relay E will be automatically transferred to the thermal relay then effective. Overload relay E will be maintained energized during a reversal of relay D, because, since back contact 15 of relay D will close before polar contact 29 reverses, an auxiliary holding circuit for relay E will be effective over back contact 15 and wire 36, to bridge the reversal time of contact 29, which contact when closed will reestablish the holding circuit through 10 the proper thermal relay contact.

15 When an overload occurs, the contact of the active thermal relay will open, breaking the holding circuit for relay E, and interrupting the motor circuit at front contact 17, whereupon the switch may be restored to its initial position by a reversal of relay D, which will pick up relay E and will select a motor circuit through the remaining thermal relay, without the necessity for waiting for the first thermal relay to cool. This 20 feature of immediate reversibility is of considerable practical importance because it eliminates traffic delays. Should the operator wish to restore the switch to its initial position from any part of its stroke, after having initiated a switch 25 movement, he may do this at any time by reversing pole-changer P. It will be apparent, therefore, that the apparatus embodying my invention provides full control of the switch at all times.

30 One feature of my invention is that it provides overload protection and makes it possible for the switch to be restored to its initial position im- 35 mediately, following an operation of the overload apparatus, by proper manipulation of the pole- changer P by the operator of the interlocking machine.

35 Although I have herein shown and described only two forms of apparatus embodying my invention, it is understood that various changes 40 and modifications may be made therein within the scope of the appended claims without departing from the spirit and scope of my invention.

Having thus described my invention, what I 45 claim is:

1. In combination, a railway switch, an electric motor for operating said switch, a polarized relay, an overload relay, a thermal relay having a heating element and a normally closed contact, 50 a pick-up circuit for said overload relay includ- 55 ing a back contact of said polarized relay and said thermal relay contact, a stick circuit for said overload relay including a front contact thereof and said thermal relay contact, circuits for said motor controlled by said polarized relay and including the heating element of said thermal relay as well as a front contact of said overload relay, a circuit for said polarized relay includ- 60 ing a pole-changer and a front contact of said over- 65 load relay, and a shunt around said overload relay contact in said polarized relay circuit which shunt includes a front neutral contact of the polarized relay.

2. In combination, a railway switch, an electric 65 motor for operating said switch, a polarized relay, an overload relay, a thermal relay having a heating element and a normally closed contact, a pick-up circuit for said overload relay includ- 70 ing a back contact of said polarized relay and said thermal relay contact, a stick circuit for said overload relay including a front contact thereof and said thermal relay contact, circuits for said motor controlled by said polarized relay and includ- 75 ing the heating element of said thermal re-

lay as well as a front contact of said overload relay, and a circuit for said polarized relay including a pole-changer and a source of current.

3. In combination, a railway switch, an electric motor for operating said switch, a polarized relay, an overload relay, a thermal relay having a heating element and a normally closed contact, means for energizing said overload relay when said polarized relay is deenergized and said thermal relay contact is closed, a stick circuit for said overload relay controlled by said thermal relay contact, circuits for said motor controlled by said polarized relay and by said overload relay and including said thermal relay heating element, a circuit for said polarized relay including a pole-changer and a front contact of said overload relay, and a shunt around said overload relay contact in said polarized relay circuit which shunt includes a front neutral contact of the polarized relay.

4. In combination, a railway switch, an electric motor for operating said switch, a polarized relay, an overload relay, a thermal relay having a heating element and a normally closed contact, means for energizing said overload relay when said polarized relay is deenergized and said thermal relay contact is closed, a stick circuit for said overload relay controlled by said thermal relay contact, circuits for said motor controlled by said polarized relay and by said overload relay and including said thermal relay heating element, and means for reversibly energizing said polarized relay.

5. In combination, a railway switch, an electric motor for operating said switch, a control relay, an overload relay, a thermal relay having a heating element and a normally closed contact, means for energizing said overload relay when said control relay is deenergized and said thermal relay contact is closed, a stick circuit for said overload relay controlled by said thermal relay contact, a circuit for said motor controlled by said control relay and by said overload relay and including said thermal relay heating element, and controlling means for said control relay.

6. In combination, a railway switch, an electric motor for operating said switch, a control relay, an overload relay, a pick-up circuit for said overload relay including a back contact of said control relay, a stick circuit for said overload relay, means responsive to the magnitude of the current supplied to said motor for governing both said pick-up and said stick circuits when said current exceeds a predetermined value, means including a front contact of said control relay as well as a front contact of said overload relay for supplying current to said motor, and means for governing said control relay.

7. In combination, a railway switch, an electric motor for operating said switch, a control relay, an overload relay, a pick-up circuit for said overload relay, a stick circuit for said overload relay, means responsive to the magnitude of the current supplied to said motor for governing both said pick-up and said stick circuits when said current exceeds a predetermined value, means governed by said control relay and said overload relay for supplying current to said motor, and means including a front contact of said overload relay for governing said control relay.

8. In combination, a railway switch, an electric motor for operating said switch, a control relay, an overload relay, a pick-up circuit for said overload relay, a stick circuit for said overload relay, means responsive to the magnitude of the current sup-

plied to said motor for governing both said pick-up and said stick circuits when said current exceeds a predetermined value, means governed by said control relay and said overload relay for supplying current to said motor, means including a front contact of said overload relay for governing said control relay, and a branch path around said overload relay contact governed by said control relay.

9. In combination, a movable device, an electric motor for operating said device, a control relay, an overload relay, a pick-up circuit for said overload relay including a back contact of said control relay, a stick circuit for said overload relay, means effective when the movement of said device becomes obstructed for governing both said pick-up and said stick circuits, means including a front contact of said control relay as well as a front contact of said overload relay for supplying current to said motor, and means for governing said control relay.

10. In combination, a movable device, an electric motor for operating said device, a control relay, an overload relay, a pick-up circuit for said overload relay, a stick circuit for said overload relay, means effective when the movement of said device becomes obstructed for governing both said pick-up and said stick circuits, means governed by said control relay and said overload relay for supplying current to said motor, and means including a front contact of said overload relay for governing said control relay.

11. In combination, a movable device, an electric motor for operating said device, a control relay, an overload relay, a pick-up circuit for said overload relay, a stick circuit for said overload relay, means effective when the movement of said device becomes obstructed for governing both said pick-up and said stick circuits, means governed by said control relay and said overload relay for supplying current to said motor, means including a front contact of said overload relay for governing said control relay, and a branch path around said overload relay contact governed by said control relay.

12. In combination, a railway switch, an electric motor for operating said switch, a polarized relay, an overload relay, a normal and a reverse thermal relay each having a heating element and a normally closed contact, a pick-up circuit for said overload relay including a back contact of said polarized relay, a normal stick circuit for said overload relay including a front contact thereof and a normal polar contact of said polarized relay as well as the contact of said normal thermal relay, a reverse stick circuit for said overload relay including said front contact thereof and a reverse polar contact of said polarized relay as well as the contact of said reverse thermal relay, a normal and a reverse circuit for said motor controlled by said polarized relay and including the heating element of said normal and said reverse thermal relay respectively and a second front contact of said overload relay, and means for reversibly energizing said polarized relay.

13. In combination, a railway switch, an electric motor for operating said switch, a control relay, an overload relay, a normal and a reverse thermal relay each having a heating element and a contact, means for energizing said overload relay when said control relay is deenergized, a normal stick circuit for said overload relay governed by said control relay and the contact of said normal thermal relay, a reverse stick circuit for said overload relay governed by said control

relay and the contact of said reverse thermal relay, a normal and a reverse circuit for said motor governed by said control relay and by said overload relay and including the heating element of said normal and said reverse thermal relay respectively, and controlling means for said control relay.

14. In combination, a railway switch, an electric motor for operating said switch, an overload relay, a normal and a reverse thermal relay each having a heating element and a contact, a normal and a reverse stick circuit for said overload relay controlled by the contact of said normal and said reverse thermal relay respectively, a normal and a reverse operating circuit for said motor controlled by said overload relay and including the heating winding of said normal and said reverse thermal relay respectively, and

manually operable means for controlling said normal and said reverse operating circuits and for energizing said overload relay.

15. In combination, a railway switch, an electric motor for operating said switch, a control relay, an overload relay, a pick-up circuit for said overload relay including a back contact of said control relay, a stick circuit for said overload relay, means responsive to the magnitude of the current supplied to said motor for governing said stick circuit when said current exceeds a predetermined value, means including a front contact of said control relay as well as a front contact of said overload relay for supplying current to said motor, and means for governing said control relay.

ROBERT M. GILSON.
